UNITED STATES PATENT OFFICE.

SIGMUND PONGO, OF NEW YORK, N. Y.

ROCKING-HORSE.

1,012,275.

Specification of Letters Patent. Patented Dec. 19, 1911.

Application filed June 7, 1911. Serial No. 631,781.

To all whom it may concern:

Be it known that I, SIGMUND PONGO, a subject of the King of Hungary, and resident of the city of New York, in the county 5 of New York and State of New York, have invented certain new and useful Improvements in Rocking-Horses, of which the following is a specification.

The present invention relates to an amusement device, and more particularly to that class in which the user is supported and carried on a body in simulation of a horse or other animal.

One of the objects of the invention is to 15 provide a simple support for a hobby-horse, or other similar device, in combination with an efficient motor operated mechanism for imparting rocking motion to said support and the device carried thereby.

Another object of the invention is to produce an improved support of the character 20 described which will hold the body of the hobby-horse, or other similar device, in a substantially horizontal position during the 25 rocking movement.

With these and other objects in view, which will appear as the nature of the invention is better understood, the same consists in the combination, arrangement and 30 construction of parts hereinafter fully described, pointed out in the appended claims and illustrated in the accompanying drawings, it being understood that many changes may be made in the size and proportion of 35 the several parts and minor details of construction without departing from the spirit or sacrificing any of the advantages of the invention.

One of the many possible embodiments of 40 the invention is illustrated in the accompanying drawings, in which:—

Figure 1 is a side elevation, partly in section, of the invention complete, and Fig. 2 is a front elevation of a detail of construction.

In the drawings, the numeral 1 indicates a 45 platform, preferably made of boards, which are supported by standards 2, 2, the latter being attached in any suitable manner to the floor. Struts 3, 3 serve to strengthen the structure. In the platform 1 are provided longitudinal slots 4, 4, through which project, above the plane of the platform, parallel rods 5, 5 and 5', 5', respectively, which 50 support a body made in simulation of a horse, although it will be easily seen that the

mechanism may as well be adapted to any other animal form or seat. The lower ends of the rods 5 and 5' are provided with eyes, in engagement with cross rods 6, 6, which 60 are fixedly attached to a base 7, the latter being secured to the floor by screws 8, 8, or otherwise. In the base are provided recesses 9, 9, which will permit of an oscillating motion of the rods 5 and 5' upon the 65 transverse rods 6, 6, which latter act as pivots for said rods. The upper ends of the rods 5 and 5', which project a considerable distance above the platform 1, are pivoted at 10 and 10', respectively, to lugs 11 and 70 11', which are fastened to the body portions of the hobby-horses 12 and 12'.

Oscillating motion is imparted to the supporting rods 5 and 5' from a rotary shaft 13, which is journaled in a bearing 14, and has 75 keyed or otherwise attached thereto cranks 15 and 15', the crank pins 16 and 16' of which are engaged by connecting rods 17 and 17', respectively, the other ends of which are pivotally attached at 18 and 18', 80 respectively, to one of the pair of connecting rods 5 and 5', respectively. Rotary motion is imparted to the shaft 13 from a motor 19, for instance an electric motor. A pulley 20 is mounted upon the shaft of this motor, and 85 over this pulley runs a belt 21, engaging also a pulley 22, which latter is keyed, or otherwise secured to the shaft 13.

The base 7 is provided upon its ends with upwardly extending projections 23, 23, 90 which carry thereon inclined pins 24, 24, upon which are shiftably arranged perforated plates 25, 25. Between these plates and the projections are located springs 26, 26 for a purpose to be described.

It will be observed that the supporting rods 5 and 5' must be arranged at a distance from each other which would allow two riders to occupy the hobby-horses 12 and 12' without interfering with each other as the 100 said hobby-horses are being rocked. Furthermore it should be observed that, while herein only two horses have been shown, it is obvious that a large number of the same could be arranged in a row, and driven from 105 a single rotary driving shaft.

The operation of the device is as follows: The riders mount the horses one after the other, when the said horses are brought as near as possible to the plane of the platform 1. The motor 19 is then started, whereby rotary motion will be imparted to

the driving shaft 13, which, in turn, will oscillate the rods 5 and 5', respectively, and thus rock the horses 12 and 12'. Since the cranks 15 and 15' are keyed at an angle to each other to the driving shaft 13 (in the case shown in the drawings at 90°), it will be observed that the horses will move one behind the other. More particularly, if one is in its lowermost position, the other will be 10 in its highest position. As one of the horses reaches its lowermost position, one of its supporting rods will compress the springs 26 above described, whereby shocks and jars will be prevented, and, on the other hand, 15 the backward movement of the horses facilitated and aided.

It is to be noted that the horses will always remain in their substantially horizontal positions by reason of their being pivotally connected to the supporting rods 5 and 5'. This latter feature is very important, particularly if the supporting rods 5 and 5' project a considerable distance above the plane of the platform 1. If the horses 20 were not kept in horizontal positions, the riders might be thrown from the same in the 25 rocking movement.

What I claim is:

1. In a device of the character described, 30 the combination with a base, of two parallel supporting bars pivoted thereto, a body made in simulation of an animal pivotally attached to the upper ends of said supporting bars, a rotary shaft, a crank keyed to said shaft, and a connecting rod between said crank and one of said supporting bars, substantially as and for the purpose specified.

2. In a device of the character described, 40 the combination with a base, of two parallel supporting bars pivoted thereto, a body made in simulation of an animal attached

by two independent pivots to the upper ends of said supporting bars, a rotary shaft, a crank keyed to said shaft, and a connecting 45 rod between said crank and one of said supporting bars, substantially as and for the purpose specified.

3. In a device of the character described, 50 the combination with a base, of two parallel supporting bars pivoted thereto, a body made in simulation of an animal pivotally attached to the upper ends of said supporting bars, a rotary shaft, a crank keyed to said shaft, a connecting rod between said 55 crank and one of said supporting bars, whereby said supporting bars and the body attached thereto are rocked, and resilient means upon said base adapted to be compressed by said bars when the latter reach 60 their outer positions in both directions, substantially as and for the purpose specified.

4. In a device of the character described, 65 the combination with a base, of two parallel supporting bars pivoted thereto, a body made in simulation of an animal attached by two independent pivots to the upper ends of said supporting bars, a rotary shaft, a crank keyed to said shaft, a connecting rod between said crank and one of said supporting 70 bars, whereby said supporting bars and the body attached thereto are rocked, and resilient means upon said base adapted to be compressed by said bars when the latter reach 75 their outer positions in both directions, substantially as and for the purpose specified.

Signed at New York, in the county of New York and State of New York, this 3rd day of June, A. D. 1911.

SIGMUND PONGO.
